UNITED STATES PATENT OFFICE.

GEORGE M. WILLIAMS, OF ELIZABETH, NEW JERSEY, ASSIGNOR TO P. LORILLARD COMPANY, OF NEW YORK, N. Y., A CORPORATION OF NEW JERSEY.

BOX-LID FASTENER.

1,174,302.

Specification of Letters Patent.

Patented Mar. 7, 1916.

Application filed October 1, 1915. Serial No. 53,517.

To all whom it may concern:

Be it known that I, GEORGE M. WILLIAMS, a citizen of the United States, residing at Elizabeth, in the county of Union 5 and State of New Jersey, have invented new and useful Improvements in Box-Lid Fasteners, of which the following is a specification.

This invention relates to box lid fasteners, 10 and has particular application to a device of this class adapted especially for use in securing, in closed position, the lid or cover of a small box such as may be used for packaging cigars, cigarettes and other 15 articles.

In the present instance it is my purpose to provide a box lid fastener which is held in position on the cover or lid of the box by frictionally engaging therewith, as contradistinguished from being rigidly fastened thereto, through the agency of small tacks, 20 teeth, spurs and other positive fasteners.

My invention thus possesses certain manifest advantages, for, as the lid or cover of 25 the box is usually composed of thin sections of wood or other fragile material which is easily split or broken, I eliminate the possibility of the lid being injured or destroyed as would be liable to occur should tacks, 30 spurs, or the like, be driven thereinto to secure the fastener in place.

Furthermore I propose to provide a fastening device adapted to frictionally engage or clamp the lid of the box, and 35 having a keeper engaging member designed to coöperate with a socket or other keeper, so that the lid, when in closed position and securely fastened, may be held against movement relative to the box body, thus preserving 40 the contents of the box from exposure and the consequent liability of damage and injury.

Another object of the invention is the provision of a fastener which is preferably 45 formed from a single blank or piece of metal, the structural simplicity of the device being such that but a comparatively small amount of material is used, and but relatively few steps are employed in its manufacture, thereby enabling great quantities 50 of these devices to be made, marketed and put in use at an exceedingly low cost.

With the above cited objects and others of a similar nature in view, my invention con-

sists in the construction, combination and 55 arrangement of parts set forth in and falling within the scope of the appended claims.

In the drawings Figure 1 is a perspective view of a box equipped with my invention. Fig. 2 is a front view of the fastener detached from the lid or cover. Fig. 3 is a bottom plan view of the fastener. Fig. 4 is a sectional view taken through a portion of the cover when closed and through the socket section of the box and showing the 60 keeper engaging portion of the fastener seated in the socket. Fig. 5 is an end view of the fastener. Fig. 6 is a plan view of the plate or blank before it is bent to form the 65 fastener.

Referring now to the accompanying drawings in detail, letter A indicates as an 70 entirety a relatively small box, such as may be employed for packaging little cigars, cigarettes and the like, this box being preferably made of small thin sections of stiff 75 material such as cedar wood. The top of the box, indicated by the numeral 1, is hinged as at 2 to the rear wall of the body of the box in any suitable manner. The top 80 edge of the front wall of the box is bored or cut out, as at 3, to constitute a socket or keeper for receiving and seating the keeper 85 engaging member of the fastener as herein-after described.

The clip member of my fastener is indicated as an entirety by the letter B and is preferably formed of a thin plate or blank of metal such as brass, sheet steel, or the like, shown in Fig. 6. The blank or plate 90 of metal is bent or folded into channel like shape or form, so that the top wing 4, the bottom wing 5 extending parallel with the top wing, and the front or connecting wall 6 result. It will be noted that the top wall 4 95 is relatively deeper than the bottom wall 5, and I preferably round the rear edge of this top wing as at 7. When the fastener clip is applied to the cover of a box, the wing 4 bears against the top face of the lid or cover, 100 the wing 5 against the opposite or bottom face of the lid or cover while the connecting wall 6, which forms the bight portion of the fastener, overlies the edge of the box cover. The bottom wall 5 is slotted longitudinally 105 as at 8—8 and the material cut from the slots is bent outward to form the resilient tongues 9—9. As will be seen these tongues

are centrally bowed outwardly as at 10 and then bent inward at their free terminals as at 11, these terminals touching with the result that the tongues possess a certain degree 5 of resiliency.

From the above description taken in connection with the accompanying drawings, the construction and manner of employing my invention will be readily apparent. 10 When in use the clip is applied to a box as shown in Fig. 1, and, when the box cover is closed, the tongues will enter the keeper socket, and, engaging with the wall of the latter, will firmly secure the box lid in 15 closed position.

It will be noted that I have provided an exceedingly simple, yet efficient device of this character, which, owing to its construction, may be manufactured, marketed and 20 applied in use in great quantities at a relatively small cost thereby attaining a considerable saving from a manufacturer's standpoint. Furthermore, the fastening device is positive in operation inasmuch as it 25 will securely hold the cover against accidental opening, and especially against yielding or working sidewise thereby insuring that when the box is carried about in the pocket it will not accidentally open and 30 cause the contents to spill or empty into the pocket.

In the present instance, I have shown my invention as employed in connection with a box intended particularly for holding small 35 cigars, cigarettes and the like, but I wish it to be understood that it is not limited in its useful application to this purpose, as it may be employed in any connection wherever in its use will be found advantageous.

40 In packing the goods for the market, after the cigars or cigarettes have been placed in the box and the lid fastened down, the usual revenue stamp may be applied so as to overlie and conceal the fastener, the 45 lower portion of the stamp being pasted to the front of the box and the upper portion to the lid, so that when the box is opened

the stamp will be torn and thus destroyed as will be readily understood.

While I have herein shown and described 50 one particular embodiment of my invention, I wish it to be understood that I do not confine myself to all the details of construction herein set forth by way of illustration, as modification and variation may 55 be made without departing from the spirit of the invention or exceeding the scope of the appended claims.

What I claim is:

1. A box lid fastener, comprising a clip 60 having a pair of spaced wings adapted to frictionally engage the opposite faces of a box lid and a bight section connecting the front portions of said wings and adapted to bear against the front edge of the lid, and 65 a plurality of resilient keeper-engaging tongues formed integral with and depending at right angles from one of said wings.

2. A box lid fastener, comprising a plate bent to channel form to provide a clip having a wing adapted to bear against the top face of a box lid, a second wing adapted to bear against the under face of the box lid, and a connecting wall forming a bight section for the clip and adapted to bear against 70 the front edge of the box lid and a keeper-engaging tongue depending from that wing which bears against the under face of the 75 box lid.

3. A box lid fastener, comprising a clip 80 bent to form a body section adapted to fit over the edge of a box cover, one section of said clip being slotted, the material of the slots being bent outwardly and oppositely bowed to form resilient tongues constituting 85 keeper engaging members.

In testimony whereof I have hereunto set my hand in presence of two subscribing witnesses.

GEORGE M. WILLIAMS.
